UNITED STATES PATENT OFFICE.

JOHN H. GILMAN, OF OTTAWA, ILLINOIS, ASSIGNOR TO KING & HAMILTON COMPANY,
OF OTTAWA, ILLINOIS, A CORPORATION OF ILLINOIS.

ADJUSTABLE SUPPORT FOR CUP ELEVATORS.

1,228,205.

Specification of Letters Patent.

Patented May 29, 1917.

Original application filed December 17, 1914, Serial No. 877,646. Divided and this application filed June 9, 1915. Serial No. 33,030.

To all whom it may concern:

Be it known that I, JOHN H. GILMAN, a citizen of the United States, and a resident of Ottawa, in the county of La Salle and 5 State of Illinois, have invented certain new and useful Improvements in Adjustable Supports for Cup Elevators, of which the following is a full, clear and exact specification.

10 My invention is concerned with certain improvements upon elevators of the class shown in prior Patent No. 1,089,125, granted March 3, 1914, to myself and Albert E. Gilman, in which a portion of a vertical 15 conveyer-trough and the included conveyer chains and cups can be folded up out of the way to allow a wagon to be driven beneath it and into dumping position, the present 20 application being a division of my application No. 877,646, filed December 17, 1914, for improvements in elevators.

In the structure shown in the aforesaid patent, while means were shown for adjustably suspending the conveyer-trough from 25 the floor above the swinging section so that it could be raised or lowered to compensate for the sagging of the floors, yet the means there shown were unnecessarily complicated and not readily manipulated. In my present 30 invention, I have provided a simple and efficient means that can be adjusted from the lower floor, which is that of the crib or barn driveway, from which the adjusting means is always accessible and easily manipulated. 35 To illustrate my invention, I annex hereto a sheet of drawings, in which the same reference characters are used to designate identical parts in all the figures, of which,—

Figure 1 is a side elevation of a portion of 40 an elevator having my improvements applied thereto; and showing the rear end of a wagon in dumping position; and

Fig. 2 is a detail in section on the line A—A of Fig. 1.

45 Elevators of the class shown in prior Patent No. 1,089,125, contain the vertical, stationary portion 10 of the conveyer trough or framework, to which is pivoted the lower portion 12 of the same framework, which is 50 adapted to be pulled by the chain 13 from the vertical operative position, shown in full lines in Fig. 1, to the horizontal inoperative position, indicated in dotted lines, to permit a wagon to drive beneath the elevator and

into the dumping position indicated. When 55 the wagon has been driven into dumping position, the lower section 12 of the framework or trough is swung down from its dotted-line to its full-line position, the hopper 14 having been previously swung out so that 60 it will have its outer end extend beneath the tail end of the wagon as the elevator section swings into place, where it is secured by the coöperation of the shoulders 15 on the locking levers 16, of which there is preferably one for each side, with the locking lugs or projections 17, which are secured to the floor of the driveway.

As the building settles after an elevator has been installed, the beams 18 constituting 70 the support for the second floor 19 are apt to sag, and consequently it is necessary to provide some suitable means for raising the elevator to keep it in the proper position relative to the floor of the driveway, and for this 75 purpose I support the upper section 10, and consequently the lower section 12, from the bars 20, which are placed on the beams 18 on either side of the section 10. On these bars 20, I place the hook members 21, which 80 have the horizontal top portions resting on the tops of the bars 20, and the lower horizontal portions 22 connected with the top portions by the web 23. Suitable studs 24 are supplied on either side of the section 10, 85 preferably by extending a rod 25 through the section and through the tops of the upper straps 26 of the hinge for the two sections. The hinge straps 26 are securely bolted to the bottom of the upper section 10, 90 and the hinge straps 26^a are similarly securely bolted to the top of the lower or 95 swinging trough-section 12, and the pivot for the hinges on either side is preferably formed by a rod 11 passing through the overlapping portions of the hinge straps 26 and 26^a. I place on the studs 24 the eyes of 100 the eye-bolts 27, which have their threaded upper ends extended through suitable apertures in the lower horizontal portions 22 of the hook members 21, so that by adjusting the nuts 28 on the ends of the eye-bolts 27, the elevator frame can be raised as much as 105 may be necessary to take care of the sagging of the beams 18. To accommodate the upward adjustment of the threaded ends of the eye-bolts 27, I bore through the beams, 20, the vertical apertures 20^a, indicated in dotted

lines in both figures, into which apertures the upper ends of the eye-bolts 27 extend if it is necessary for them to be raised that much.

5 What I claim as new, and desire to secure by Letters Patent of the United States, is:

1. In an elevator, the combination with the joists of the building, of a vertical framework depending through and between the joists, supporting beams resting on the joists, hook members having their uppermost horizontal flange resting on the beams, studs projecting from the sides of the framework, eye-bolts having their eyes over the studs 15 and having their threaded ends extending upward through the lower horizontal flanges of the hook members, and nuts coöoperating with the bolts and hook members to regulate the height of the framework.

20 2. In an elevator, the combination with the joists of a building, of a vertical framework depending through and between the joists, a swinging frame portion hinged to the stationary portion below the joists,

hinges comprising hinge straps secured to 25 the bottom of the stationary frame section and to the top of the swinging section, a hinge rod passing through the overlapping ends of the hinge straps, a suspension rod 30 passed through the stationary frame section and the upper ends of the upper hinge straps, supporting beams resting on the joists, hook members having their uppermost horizontal flanges resting on the beams, eye-bolts having their eyes over the outer 35 ends of the suspension rod and having their threaded ends extending upward through the lower horizontal flanges of the hook members, and nuts coöoperating with the bolts and hook members to regulate the 40 height of the framework.

In witness whereof, I have hereunto set my hand and affixed my seal, this 4th day of June A. D. 1915.

JOHN H. GILMAN. [L. S.]
